SCREENING APPARATUS

Gerhard Linke, Magdeburg, Germany, assignor to
the firm Fried. Krupp Grusonwerk Aktiengesellschaft, Magdeburg-Buckau, Germany

Application December 14, 1931, Serial No. 580,984
In Germany December 12, 1930

3 Claims. (Cl. 209—403)

It has been found that screen cloth which is rigidly fixed in the screen frame has a tendency to blinding. On the other hand if the screen cloth is but loosely fitted between cleats of the screen frame, the cloth is free to set up its own motion or to flap, and thus the screen cloth wears out in a relatively short time, the cloth breaking mostly at those points where it is clamped down. In addition to this drawback, the oscillations set up by such a flapping screen cloth are entirely irregular, nodes or node-lines being formed along the screen cloth whereby the same is subjected to severe bending stresses. Where as some portions of the screen cloth remain tranquil or are only slightly oscillating, other portions oscillate with considerable lag in their oscillation phases, which sometimes differ as much as 180° from those of the screen frame.

It is obvious that a screen cloth oscillating too irregularly cannot satisfy the severe demands required during the screening process and that the screening efficiency must necessarily be impaired. Above all such a screen cloth cannot transport satisfactorily the screen-feed.

The present invention has for its object to eliminate the above mentioned disadvantages by the provision of a screening apparatus in which the subdivision of the entire screen surface into several individual fields of vibration is effected by adjustable tuning-in cleats. In this way it is possible to tune-in each of the individual fields of vibration and thus consequently also the entire screen surface to the frequency of oscillation imparted to the screening apparatus.

The accompanying drawing illustrates several ways in which the invention may be practically executed.

Fig. 1 shows a longitudinal section through a screen frame.

Fig. 2 shows the cross section corresponding to Fig. 1.

Fig. 3 shows a longitudinal section through a different embodiment of a screen.

Fig. 4 is a plan view of Fig. 3.

In a screen frame 1, beams 2 are disposed longitudinally, and tuning-in cleats or supporting rods 3 are so arranged as to rest transversely on top of those beams. These cleats can be shifted along the longitudinal axis of the frame and can be clamped down in any position by the aid of the screws 4 provided on both ends of each cleat. The screws are guided by longitudinal slots 5 in the screen frame and the ends of the screws protrude out of these slots. The screen cloth 6 rests on the cleats 3 and it is then stretched tight

at will through a tension device acting along the longitudinal axis of the screen frame. The tops of the cleats or supporting rods 3 are disposed at a higher elevation than the ends of the screen cloth 6, thereby forming a crowned screen divided into sections. The tension device consists of screws attached to one end of the screen cloth, the screw heads passing through the screen frame and the lock washers 8, the screw nuts pressing against the latter. The other end of the screen cloth is fixedly attached to the screen frame.

It has been found that by proper adjustment of the cleats 3 the individual fields of vibration thus formed by these cleats can be tuned-in to the frequency of oscillation imparted to the screen frame in such a manner as to render the system dissonant so that the amplitudes of oscillation of the screen cloth will nowhere exceed the proper limit and that the screen feed will be uniformly propelled across the screen surface. For the satisfactory functioning of the screening apparatus it is of great importance to render all parts of the substructure of the screen so rigid that no interfering secondary oscillations can be excited in these parts. This required rigidity may also be accomplished by stiffening the said substructure by some supporting device.

The cleats 3 are also adjustable in their vertical position independently of each other. In this way the propelling velocity of each of these individual screen parts can be regulated independently.

Figs. 3 and 4 illustrate a design of this screening apparatus, which provides for the adjustability both of the cleats 3 and the beams 2, thus permitting the variation in area of the fields of vibration both in longitudinal and transverse directions, as indicated by the arrows in Fig. 4. The top edges of the beams in this case support the screen 6.

What I claim is:—

1. A vibrating screening apparatus, comprising a longitudinally extending rigid frame, a screening surface disposed upon said frame, a plurality of transversely extending supporting rods for said screening surface mounted directly on said rigid frame and having the tops thereof disposed at a higher elevation than the ends of said screening surface to form a crowned screen divided into sections, and means for separately adjusting said rods longitudinally along said frame to different supporting positions, whereby the fields of vibrating surfaces defined

by said supporting rods may be varied to impart dissonance thereto.

2. A vibrating screen apparatus comprising a longitudinally extending frame, a screening surface disposed upon said frame, a plurality of beams extending longitudinally of the frame and supporting the said screening surface upon the underside thereof, said beams being adjustable in a transverse direction, a plurality of aligned recesses at the top edges of said beams, a plurality of supporting rods for said screening surface supported by said beams at said recesses to support said screening surface at the underside thereof, and means for separately adjusting said rods to different supporting positions whereby the fields of vibrating surfaces defined

by said supporting rods and beams may be varied to impart dissonance thereto.

3. In a vibrating screening apparatus, a rigid frame, a screening surface, transverse rods for supporting said surface across the whole width thereof mounted directly on said rigid frame and having the tops thereof disposed at a higher elevation than the ends of said screening surface to form a crowned screen divided into sections, and means for separately adjusting said rods in the longitudinal direction of said screening surface to different supporting positions, whereby the fields of vibrating surfaces defined by said supporting rods may be varied to impart dissonance thereto.

GERHARD LINKE.
